MULTICONTACT BIMETALLIC THERMAL RETARDER FOR ELECTRIC WATER HEATERS

Clark M. Osterheld, Stoughton, Wis., assignor to
McGraw Electric Company, Elgin, Ill., a corporation of Delaware

Application September 20, 1944, Serial No. 554,999

4 Claims. (Cl. 219—39)

1

My invention relates to electric heater control devices, and particularly to thermal retarder heater control switch units.

An object of my invention is to provide a relatively simple and easily manufactured structure to selectively cause either immediate energization of the electric heater of a domestic hot water tank, or energization of the heater with a predetermined time delay period, in accordance with the amount of cold water in the tank at the start of an off-peak period.

Another object of my invention is to provide a means controlled by the thermal element of a thermal retarder having a heating coil on the thermal element, to control the energization of the heating coil in accordance with the position of the thermal element.

In the drawings,

Figure 1 is a vertical, sectional view of a water tank with a thermal retarder embodying my invention associated therewith.

Fig. 2 is a diagram of circuits showing the positions of the contacts when the tank is either entirely full of cold water or is at least half full of cold water.

Fig. 3 is a diagram of circuits showing the positions of the contacts when the tank is more than half full of hot water in its upper portion and cold water in its lower portion.

Fig. 4 is a diagram similar to Fig. 3, except the positions of the contacts are shown at the end of a retarding period.

Fig. 5 is a modified diagram of circuits embodying a relay which is shown as being deenergized.

Fig. 6 is a top plan view of a thermal retarder embodying my invention shown in horizontal section.

Fig. 7 is a fragmentary, horizontal, sectional view therethrough taken on the line 7—7 of Fig. 8.

Fig. 8 is a view in side elevation of my improved thermal retarder, with the cover shown in section and when the tank contains cold water at its center portion.

Fig. 9 is a front elevational view of the device shown in Fig. 8, with the cover shown in section, and.

Fig. 10 is a modified diagram of circuits showing a shunting of the heating coil of the bimetal bar when the tank contains cold water at the center portion.

Referring first to Fig. 1 of the drawings, I have there shown an ordinary domestic hot water tank 21 having a lower cold water inlet pipe 23, an upper hot water outlet pipe 25, a layer 27 of heat-

2

insulating material therearound, which latter is held in place by an outside casing 29.

I provide also a single electric heater 31, which may be of the clamp-on type and be located in a tunnel member 33. All of these hereinabove elements are old and well known in the art and constitute no part of my present invention.

I provide a lower thermally-actuable heater control switch, designated generally by the numeral 35, which, while it may be of any kind effective for the given purpose, is shown as comprising a bimetal bar 37, one end of which is fixedly mounted on a contact 39, while the other end thereof is adapted to engage with and be disengaged from a second fixed contact 41, which two contacts are insulatedly mounted against the outside of the tank so that the bimetal bar 37 will be subject to the temperature of the water in the tank. The design, construction, and adjustment 10 of the thermally-actuable switch 35 is such that it will be in closed position when subject to cold water in the tank and will be in open position when subject to hot water in the tank. Any desired known method and means may be employed 15 to effect such opening and closing movements under the conditions of cold water having a temperature on the order of 60° to 70° F. and hot water having a temperature on the order of 150° F.

Referring now particularly to Figs. 6, 7, 8, and 30 9, I have there shown a thermal retarder, which is a modification of that shown and claimed in my copending application, S. N. 554,998 filed September 20, 1944, and assigned to the same assignee as is the present application. The thermal retarder 43 is adapted to be secured against the outer surface of a supporting block 45, whose inner surface is of arcuate shape to fit against the outer arcuate surface of the tank 21, and the block 45 may be held in fixed position by welding 35 seams 47. The thermal retarder assembly 43 includes a bracket 49, which latter is of substantially L-shape, the vertically-extending portion thereof being adapted to be secured against the outer surface of block 45 by a plurality of short 40 machine screws 51. The bracket 49 includes a longitudinally, vertically-extending projection 53 having a short, flat, vertical surface at its lower portion, against which the lower end of a bimetal bar 55 may be secured as by a pair of machine 45 screws 57. The bimetal bar 55 is relatively long and of the creep-type, that is, its flexure, with change of temperature, is substantially uniform with the change of temperature.

I provide a horizontally-projecting bracket 55 member 59 secured by a pair of short machine

screws 61 against one side of member 53. A block 63, of electric-insulating material, which is of substantially rectangular shape and has a vertical recess 65 in its upper surface, is secured against a front flattened portion 67 of member 59 by screws 69. Members 53 and 63 are provided with aligned openings 71, 73, and 75 therein for a purpose which will hereinafter appear. A long headed rod 77, having a screw-threaded inner end, is adapted to extend through the aligned openings 71, 73, and 75, a block 78 of electric-insulating material and of generally tubular shape being located on the central portion of rod 77 and being adapted to be moved thereon by the bimetal bar 55, which is provided with a forked upper end adapted to be engaged between two collars 79 and 81 on the inner end of member 78. The inner reduced end portion of member 78 has a coil spring 83 thereon having one end engaging the collar 81, while the other end engages a collar 85 of electric-insulating material, which collar is adapted to engage a contact bridging member 87 slidably mounted on the inner reduced portion of member 78. The contact bridging member 87 is adapted to engage with and be disengaged from contact members 89 and 91, which are mounted on the inner vertical surface of block 63.

I provide a second coil spring 93, which is located on the outer end portion of rod 77 between the head of rod or bolt 75 and a collar 95 of electric-insulating material, slidably mounted on rod or bolt 77, the spring 93 being effective to hold the collar 95 away from the head of bolt 77. A second contact bridging member 97 is mounted on collar 95 and is adapted to engage with and be disengaged from a pair of fixed contacts 99 and 101, when the bimetal bar 55 has moved the member 78 as far to the right as is possible and contact bridging member 97 is adapted to engage with a pair of fixed contacts 103 and 105, which are positioned on the inner surface of the outer projection of member 63, when member 78 is moved as far as possible to the right. The contact members 89, 99, and 103 are all electrically connected together, as are also contacts 101 and 105. I provide a cover 107, which may be held in proper operative position as by machine screws 109.

The bimetal bar 55 is shown in Fig. 8 of the drawings, in full lines, in the position which it will occupy when subject to cold water in the tank. While I preferably mount the thermal retarder 43 at the mid-height of the tank, I do not desire to be limited thereto, and any statement as to the tank being half full of cold water, so that the bimetal bar 55 is subject to cold water and being half full of hot water, so that bimetal bar 55 is subject to hot water, is to be understood as being subject to slight alterations. The bimetal bar 55 is adapted to be in position 111, shown in broken lines in Fig. 8 of the drawings, when subject to hot water, by which I mean water having a temperature on the order of 150° F. A small heating coil 113 is insulatedly mounted on the outer movable end of bimetal bar 55, and when energized for a period of time, on the order of four to six hours, it will cause flexure of the bimetal bar 55 in a clockwise direction to the position designated by 115 in broken lines in Fig. 8 of the drawings. Heating coil 113 is effective to cause a rise of temperature of the outer end of bimetal bar 55 to a value on the order of 250° F. or more in from four to six hours.

Referring now to Figs. 2, 3, and 4 of the drawings, I have there shown a diagram of connections, including the lower thermally-actuable heater control switch 35, the thermal retarder 43, and a time-controlled switch 117, shown generally only as including a pair of contact arms 119 and 121. It is to be understood that the time-controlled switch 117 is controlled by a continuously operative timer, either of the clock kind or of the electric motor kind, so that the two contact arms will be out of engagement with each other during on-peak periods but will be in engagement with each other during off-peak periods of a twenty-four hour day.

I provide a pair of supply circuit conductors 123 and 125, of which conductor 123 is connected to contact arm 119. The second contact arm 121 of the time-controlled switch is connected by a conductor 127 with contacts 103, 99, and 89. Contact 91 is connected by a conductor 129 with one terminal of heating coil 113, the other terminal of which is connected by a conductor 131 with contact 41 of the lower thermally-actuable switch 35. A conductor 133 connects contact 41 to one terminal of heater 31, the other terminal of which is connected by a conductor 135 with terminal 105 of the thermal retarder switch, which is electrically connected to the other contact 101. Contact 39 of the lower thermal switch 35 is connected by a conductor 137 with the second supply circuit conductor 125.

Referring first to Fig. 2, I have there shown the contacts in the positions they will occupy when the tank is more than half full of cold water, so that the lower thermal switch 35, as well as the thermal retarder switch 43, will be subject to cold water, with the result that bimetal bar 37 will engage contact 41, and contact bridging member 97 will engage contacts 101 and 99, because of the fact that bimetal bar 55 is flexed in a counter-clockwise direction to the limit of its movement.

If this condition occurs during on-peak periods, that is, say, before 10 p. m., the fact that the time-controlled switch is still open will prevent energization of heater 31, but when time-controlled switch 117 is closed at the start of an off-peak period, which we may assume to happen at 10 p. m., then the following energizing circuit is established through heater 31: from supply circuit conductor 123 through engaged contact arms 119 and 121, through conductor 127 to contacts 103 and 99, through bridging member 97, through contacts 101 and 105, through conductor 135 heater 31, conductor 133, through closed switch 35, and from there through conductor 137 to the second supply circuit conductor 125.

Energization of the heater 31 will continue until the tank 21 is more than half full of hot water at the top portion, so that thermal retarder 43 will be subject to hot water, the bimetal bar 55 being flexed thereby into position 111, with the result that the diagram of connections is now as shown in Fig. 3 of the drawings, where contact bridging member 87 is in engagement with contact members 89 and 91, while contact bridging member 97 is out of engagement with contact members 99 and 101. This new position of bimetal bar 55 will close an energizing circuit through heating coil 113 on bimetal bar 55 through a circuit as follows: from supply circuit conductor 123 through engaged contact arms 119 and 121, conductor 127 through contact member 103 to contact member 89, through bridging member 87 to contact 91, through conductor 129,

heating coil 113, conductor 131, through closed switch 35, and from there through conductor 137 to the second supply circuit conductor 125. As has already been hereinbefore stated, the time necessary to cause heating up of the bimetal bar 55 to a temperature on the order of 250° F., sufficient to cause flexure thereof to the position shown in Fig. 8, by numeral 115, is on the order of, say, four hours. When this heating up of bimetal bar 55 occurs, the positions of the contacts will be that shown in Fig. 4 of the drawings, with the result that the heater coil 31 is energized through substantially the same circuit as hereinbefore noted, except that contact bridging member 87 is now in engagement with contacts 103 and 105. Energization of heater 31 will therefore continue until either all of the water in the tank is hot before the end of the off-peak period, with resultant opening of the lower thermal heater control switch 35, or in case less than all of the water in the tank is hot at the end of an off-peak period, heater 31 will be deenergized by opening of the time-controlled switch 117 at the end of an off-peak period.

This will deenergize not only the heater 31, but also heating coil 113, with the result that since the thermal retarder 43 is subject to hot water, the parts will move back to the positions shown in Fig. 3 of the drawings, so that the entire system is deenergized.

The device and system embodying my invention, as thus far described, is therefore effective to cause a predetermined time period of delay in the energization of the heater 31 after the tank is half full of hot water.

Referring now to Fig. 5 of the drawings, I have there illustrated another system embodying the thermal retarder and including, in addition to the thermal retarder, the time-controlled switch and the lower thermally-actuable switch, an electromagnetic switch for controlling the energization of the heating coil on the bimetal bar. The electromagnetic switch, designated generally by numeral 139, comprises a pair of fixed contacts 141 and 143, a contact bridging member 145, adapted to be moved into and out of engagement with the fixed contacts and connected with a magnetizable core 147, which is adapted to be energized by a coil 149. Contact 143 is connected by a conductor 151 with contact 41 of the lower thermal switch. Contact 141 is connected by a conductor 153 with one terminal of the heating coil 113, while the other terminal of heating coil 113 is connected by a conductor 155 with contacts 89, 99, and 103. One terminal of coil 149 is connected by a conductor 157 with contact 143, while the other terminal of coil 149 is connected by a conductor 159 with contact 91 of the thermal relay.

The position of the contacts in Fig. 5 of the drawings is that occupied by them when the thermal retarder is subject to cold water in the tank during an on-peak period. It is evident that at the start of an off-peak period the time-controlled switch 117 will be closed and thereby provide the hereinbefore described circuit for energizing the heater 31. When more than half of the water in the tank has been heated, and the bimetal bar 55 has been moved into its intermediate position, designated by numeral 111 in Fig. 8 of the drawings and shown schematically in Fig. 3 of the drawings, an energizing circuit for the coil 149 of the electromagnetic switch 139 will be closed by engagement of contact bridging member 87 with contacts 89 and 91. This cir-

cuit is as follows: from supply circuit conductor 123 through engaged contact arms 119 and 121, through conductor 127 to contacts 103 and 89, through bridging member 87 to contact 91, through conductor 159, coil 149, conductor 157 to contact 143, through conductor 151 to contact 41, through closed switch 35, and from there through conductor 137 to the second supply circuit conductor 125. This energization of coil 149 will cause quick upward movement of the contact bridging member 145, with the result of closing an energizing circuit through heating coil 113 substantially as follows: from supply circuit conductor 123 through closed time-controlled switch 117, conductor 127 to contact 103, through conductor 155, heating coil 113, conductor 153, through engaged contacts 141 and 143 with contact bridging member 145, through conductor 151 to contact 41, through closed switch 35, and from there through conductor 137 to the second supply circuit conductor 125. The heating coil 113, thus energized, will cause slow temperature rise of the bimetal bar 55 until, at the end of a predetermined time period, say four hours, the bimetal bar 55 will have flexed in a clockwise direction to position 115, whereby an energizing circuit through heater 31 is closed, as has already been hereinbefore described and as is shown in Fig. 4 of the drawings. The system shown schematically in Fig. 5 of the drawings is therefore effective to cause energization of heater 31 a predetermined time after at least one-half the water in the tank is hot, and bimetal bar 55 will have been moved to position 111, shown in Fig. 8 of the drawings.

Referring now to Fig. 10 of the drawings, I have there illustrated a still further modification of circuit embodying my invention, in which the thermal retarder shown in Figs. 6, 7, 8, and 9 is effective to control the energization of heating coil 113 in a somewhat different manner.

The terminals of the heating coil 113 are connected to contacts 89 and 91 as by conductors 161 and 163. Contact 91 is connected by a conductor 165 to one terminal of a fixed current limiting resistance 167, the other terminal of which is connected by a conductor 169 to contact 41 of the lower thermally-actuable switch 35. The contact bridging member 87 adapted to engage with and be disengaged from contacts 89 and 91 is now positioned on the other side of the contact members 89 and 91, and while I have not shown such a structure specifically, it is thought unnecessary to do so, since the change could very easily be made. When the second contact bridging member 97 is in engagement with contacts 99 and 101, then contact bridging member 87 is in engagement with contacts 89 and 91, thereby short-circuiting heating coil 113, making it ineffective to cause heating of the bimetal bar 55 during the time that heater 31 is energized because of the presence of cold water in the tank, amounting to more than half of a full tank. When the time switch 117 is closed, as during an off-peak period, and assuming that more than half of the tank full of water is hot, the bimetal bar 55 will have been moved into position 111, whereby contact bridging member 97 is moved out of engagement with contacts 99 and 101, and contact bridging member 87 is moved out of engagement with contacts 89 and 91, whereby an energizing circuit through heating coil 113 is closed as follows: from supply circuit conductor 123 through engaged contact arms 119 and 121, through conductor 127 to contact 89, through conductor 161, heating coil 113,

conductor 163, contact 91, conductor 165, resistance 167, conductor 169, through closed switch 35, and from there through conductor 137 to the second supply circuit conductor 125. This will energize heating coil 113, with the result that bimetal bar 55 will flex in a clockwise direction after a delay period on the order of four hours or more to cause contact bridging member 97 to move into engagement with contacts 103 and 105, whereby the hereinbefore described energizing circuit through heater 31 is closed. Energization of heater 31 will continue until either substantially all of the water in the tank is hot before opening of the time-controlled switch, in which case thermal switch 35 will open to deenergize the system, or in case less than all of the water in the tank is hot at the end of an off-peak period, opening of the time-controlled switch 117 will deenergize the heater 31.

It is thus evident that the several systems shown in various views in the drawings, and particularly the thermal retarder shown in Figs. 6, 7, 8, and 9, are effective to cause a time delay of predetermined length after closure of the time-controlled switch, when the tank is more than half full of hot water, at the end of which delay period energization of the heater is resumed and continued until either all of the water in the tank is hot, if this happens before the end of the off-peak period, or continues until the end of the off-peak period.

Various other modifications may be made in the systems embodying my invention without departing from the spirit and scope thereof, and all such modifications coming clearly within the scope of the appended claims are to be considered part of my invention.

I claim as my invention:

1. In a thermal retarder switch unit for a hot water storage tank heater to be mounted on a tank intermediate its ends and comprising a heater, a pair of contact bridging members, a bimetal bar operatively connected to said bridging members to actuate the same, three pairs of stationary contact members to be engaged with and disengaged from said bridging members when actuated by said bimetal bar, a heating coil supported by the free end of said bimetal bar, the energization of which is controlled by the first of said contact bridging members and the first pair of cooperating contact members, the second and third pair of contact members being connected in parallel with each other and in series with said heater, said second contact bridging member being moved into engagement with said second pair of contact members when said bimetal bar is subject to cold water in the tank and moved into engagement with said third pair of contact members after a predetermined time period of delay after energization of said heating coil.

2. In a thermal retarder switch unit for a hot water storage tank heater to be mounted on a tank intermediate its ends and comprising a heater, a pair of contact bridging members, a bimetal bar operatively connected to said bridging members to actuate the same, three pairs of stationary contact members to be engaged with and disengaged from said bridging members when actuated by said bimetal bar, a heating coil supported by the free end of said bimetal bar, the energization of which is controlled by the first of said contact bridging members and the first pair of cooperating contact members, the second and third pair of contact members being connected in parallel with each other and in series with

said heater, said second contact bridging member being moved into engagement with said second pair of contact members when said bimetal bar is subject to cold water in the tank to energize said heater and said first contact bridging member is moved into engagement with said first pair of contact members to energize said heating coil when said bimetal bar is subject to hot water in the tank and said second contact bridging member is moved into engagement with said third pair of contact members after a predetermined time period of delay after energization of said heating coil.

3. In a thermal retarder switch unit for a hot water storage tank heater to be mounted on a tank intermediate its ends and comprising a heater, a pair of contact bridging members, a bimetal bar operatively connected to said bridging members to actuate the same, three pairs of stationary contact members to be engaged with and disengaged from said bridging members when actuated by said bimetal bar, a heating coil supported by the free end of said bimetal bar, the energization of which is controlled by the first of said contact bridging members and the first pair of cooperating contact members, the second and third pair of contact members being connected in parallel with each other and in series with said heater, said second contact bridging member being moved into engagement with said second pair of contact members when said bimetal bar is subject to cold water in the tank to energize said heater and said first contact bridging member is moved into engagement with said first pair of contact members to energize said heating coil and said second contact member is moved out of engagement with said second pair of contact members when said bimetal bar is subject to hot water in the tank.

4. In a thermal retarder switch unit for a hot water storage tank heater to be mounted on a tank intermediate its ends and comprising a heater, a pair of contact bridging members, three pairs of stationary contact members, a bimetal bar operatively connected to said contact bridging members to actuate the same into and out of engagement with said stationary contact members, a heating coil carried by said bimetal bar, an electromagnetic switch controlling the circuit of said heating coil, the coil of said electromagnetic switch being controlled by one of said bridging members and one of said pair of stationary contact members, said bimetal bar holding said second bridging member in engagement with said second pair of contact members when subject to cold water and holding said first bridging member in engagement with said first pair of contact members and said second bridging member out of engagement with any contact members when said bimetal bar is subject to hot water in the tank and holding said second bridging member in engagement with said third pair of contact members to energize said heater after a predetermined time delay after energization of said heating coil.
